United States Patent Office

Des. 191,207
Patented Aug. 29, 1961

191,207

TELESCRIBER

Thomas B. Quinn, Los Angeles, Calif., assignor to Tel-autograph Corporation, Los Angeles, Calif., a corporation of Virginia

Filed Dec. 9, 1960, Ser. No. 63,181

Term of patent 14 years

(Cl. D26—14)

FIG. 1 is a front perspective view of a telescriber embodying my design; and

FIG. 2 is a rear elevation of the telescriber of FIG. 1.

I claim:

The ornamental design for a telescriber, substantially as shown.
